UNITED STATES PATENT OFFICE.

EDWARD W. GROGAN, OF BYERS, TEXAS.

AUTOMATIC DOOR-CLOSER.

1,092,041.

Specification of Letters Patent. Patented Mar. 31, 1914.

Application filed March 8, 1912. Serial No. 682,348.

To all whom it may concern:

Be it known that I, EDWARD W. GROGAN, citizen of the United States, residing at Byers, in the county of Clay and State of Texas, have invented certain new and useful Improvements in Automatic Door-Closers, of which the following is a specification.

This invention relates to improvements in automatic door closers, and has for one of its objects to simplify and improve the construction and increase the efficiency and utility of devices of this character.

Another object of the invention is to provide a simply constructed device which may be applied to doors of various sizes such as the ordinary door, screen doors, or the like, whereby the door may be caused to close without slamming or jarring.

Another object of the invention is to provide a simply constructed device which may be readily adjusted to increase or decrease the tension and thus control the movement of the door and adapt the device to doors of different sizes and weights.

Another object of the invention is to provide a simply constructed device of this character which may be applied to a right or left hand door by simply reversing the parts and without altering any of the parts.

With these and other objects in view, the invention consists in certain novel features of construction as hereafter shown and described, and then specifically pointed out in the claims, and in the drawings illustrative of the preferred embodiment of the invention: Figure 1 is a front elevation of the improved device applied including a portion of a door casing, frame, and the upper portion of a screen door; Fig. 2 is an enlarged plan view from beneath, partly in section, of the improved device applied; Figs. 3 and 4 are perspective views of the detachable covers; Fig. 5 is a transverse section on the line 5—5 of Fig. 2; Fig. 6 is a perspective view of a modified form of a portion of the device.

Corresponding and like parts are referred to in the following description and indicated in all the views of the drawings by the same reference characters.

The improved device comprises two gen-

eral portions, a portion adapted to be attached to the door and another portion adapted to be attached to the jamb or frame. 55 The portion which is attached to the jamb or frame of the door comprises a casing or frame represented as a whole at 10 formed with longitudinal compartments 11 and 12 spaced apart and divided by an intermediate 60 dividing member 13 with guide ribs 14 to receive a cover member 15. The cover is detachably secured upon the casing or frame by a screw or other suitable fastening device 16. The cover 15 is removable from one end 65 only of the frame and the latter is provided with a stop lip 17 to limit the movement of the cover in one direction.

Extending transversely of the casing 10 near one end is a partition 18, the dividing 70 member 13 terminating at the partition as shown. The casing 10 together with its dividing member 13, partition 18, and guide lips 14, will preferably be cast in one single piece, while the cover member 15 will likewise be cast in one piece and slidably engaged with the casing. Located respectively within the compartments 11—12 are springs 19—20, the springs preferably being of the coiled form and provided respectively with 80 pull rods 21—22. The pull rod 21 is provided at the inner end with adjusting nuts 23, while the pull rod 22 is provided at its inner end with similar adjusting nuts 24. Pivoted at 25 in the casing 10, is a lever arm 85 26, the lever arm being divided or forked at the inner end and coupled respectively by links 27—28 to the rods 21—22. The springs 19—20 bear at one end against the partition 18 so that as the lever arm 26 is oscillated 90 upon its pivot 25, the springs will be alternately compressed. Thus when the lever arm is moved in one direction the spring 19 will be compressed and when the lever arm is moved in the opposite direction the spring 95 20 will be compressed, the object to be hereafter explained.

Segmental plates 30 are united at 29 and each provided with a plurality of apertures 31 concentric to the plate uniting bolt 29, as 100 shown. At its outer end the lever arm 26 is formed with a disk 32 having a plurality of circularly arranged apertures 33 one of which is adapted to be connected by a pin or

other fastening device 34 to one of the apertures 31 of the segmental plate.

The door frame or jamb is indicated conventionally at 55, while the door is indicated conventionally at 35.

Attached to the door 35 preferably opposite the casing 10 when the door is closed, is another casing represented as a whole at 36, and having a transverse stop partition 37, and located within the casing 36 and bearing against the partition, is another spring 38 through which a pull rod 39 extends, and is provided with an adjusting nut 40 at its inner end. Pivoted at 41 in the casing 36, is a lever arm 42 having an offset 43 to receive the pivot 41 and connected by a link 44 to the rod 39. By this means it will be obvious that the force of the spring 38 operates to maintain the lever arm 42 in withdrawn position. At its outer end the lever arm 42 is adjustably connected to an outer member 45 having a disk 46 at its outer end provided with a plurality of circularly arranged apertures 47 with one of which a pin 48, which extends through the segmental plate 30, engages. The member 45 is provided with guideways 49 in which the outer end of the lever 42 is slidably engaged. The lever 42 is provided with a plurality of apertures 50 with which a pin 51, which extends through the member 45, engages one at a time to adjustably couple the members 42 and 45. The lever arm 26 is provided with a plurality of apertures 52 with one of which a spring 53 is connected at one end, while the opposite end of the spring is connected to a pin 54 in the segmental plate 30. The spring 53 thus exerts its force to hold the lever 26 yieldably coupled to the segmental plate, and thus serves to retard the closing action and prevent the door closing too quickly, and thus acts as a governor to the improved device, as will be obvious. If the door closes too quickly the spring 53 is "hooked back" in one of the holes 52 of the lever 26 to increase its tension, or if the door closes too slowly the tension of the spring 53 may be reduced by hooking it forwardly in one of the holes 52. The spring 53 may thus be adjusted to control the movement or action of the levers and prevent them from operating loosely at certain points.

With the device thus constructed it will be obvious that the spring 19 exerts its force to hold the door yieldably closed, and when the door is opened, the spring 38 pulls directly against the spring 20, while at the same time the rod 21 moving inwardly, relaxes the spring 19, and then when the door is released the springs 20 and 38 coact to close the door and at the same time the rod 21 is drawn outwardly and just before the door closes, the spring 19 begins to compress and thus checks the closing of the door and prevents slamming or jarring. As be-

fore noted, all of the springs are adjustable to control the tension through the medium of the adjusting nuts 23-24 and 40, so that the exact degree of tension can be applied to the springs to cause them to effectually coact to produce the desired results. The ability to adjust the springs also enables the device to be readily adapted to doors of different sizes and weights and to cause the device to operate at any speed required. By providing a plurality of the apertures 52 the tension of the governor spring 53 may likewise be controlled, and by providing a plurality of apertures 31-33 and 47 in the segmental plate and in the levers, the latter may likewise be adjusted to any required extent. Again by providing the member 42 with a plurality of apertures for the pin 51, the lever 42 may be adjusted to correspond to the tension of the spring 38. The spring 20 will be maintained at a relatively strong tension, while the spring 19 is maintained sufficiently slack to become operative at the proper moment to check the closing movement and prevent slamming or jarring so that the door closes with ease and without noise. The spring 53 also operates to assist in the slow closing of the door, and acts as a governor to the movements of the levers. If the door closes too quickly, the governor spring 53 will be adjusted in the holes in the lever 26, to tighten this spring slightly so as to impart the proper tension according to the weight of the door.

To reverse the closing mechanism from a left hand to a right opening door, or vice versa, it is only necessary to simply reverse the position of the casing 10 to the left or right hand edge of the door as the case may be and likewise transpose the tension of the springs, or arrange the spring 19 so that it operates as the closing spring while the spring 20 is loosened or slackened off and caused to operate as the checking spring.

The lever 26 may be detached from the pivots 25 and 34 and reversed in position together with the springs 19-20 which will produce the same effect when the casing 10 is changed from a left to a right hand door, or vice versa as above described, instead of transposing the tension of the springs.

The improved device is simple in construction, can be inexpensively manufactured and applied without structural change either in the door or in the frame or jamb and likewise adapted without structural change to doors of varying sizes by simply adjusting the tension of the various springs and the pivotal points of the levers.

It will be obvious that the "leverage" may be also adjusted to the size or weight of the door by changing the position of the pivots 34 and 48 relative to the apertures 31 and 33 and 47. By this arrangement the improved device is readily adapted to all the

various sizes and weights of doors in common use without structural change either in the doors or the apparatus.

The member 45 may be constructed in the 5 form shown in Fig. 6 with a lateral offset and thus adapt the device to doors which are lower than the top of the casing, and thus obviate the necessity for employing a spacing block to support the frame 36.

10 The casing 36 is provided with a closure 56 slidably connected thereto, so that access may be readily had to the interior of the casing to adjust the spring 38 through the medium of the adjusting nut 40.

15 Having thus described the invention, what is claimed as new is:

1. In a door closer, stationary abutments carried respectively by a door and a door frame, a lever pivotally supported adjacent to each of said abutments, a member movably coupling said levers, a closing spring and a checking spring bearing against one of said abutments, means for coupling said closing spring and checking spring respectively to one of said levers at opposite sides of its pivot, another closing spring bearing against the other abutment, and means for coupling said last mentioned closing spring to the other lever at one side of its pivot.

20 2. In a door closer, stationary abutments carried respectively by a door and a door frame, a lever pivotally supported adjacent to each of said abutments, a member movably coupling said levers, a governor spring connecting one of said levers with said coupling member, a closing spring and a checking spring bearing against one of said abutments, means for coupling said closing spring and checking spring respectively to one of 25 said levers at opposite sides of its pivot, another closing spring bearing against the other abutment, and means for coupling said last mentioned closing spring to the other lever at one side of its pivot.

30 3. In a door closer, stationary abutments carried respectively by a door and a door frame, a lever pivotally supported adjacent to each of said abutments, a member movably coupling said levers, a closing spring bearing against one of said abutments, means for coupling said closing spring to one of 35 said levers at one side of its pivot, another closing spring bearing against the other abutment, and means for coupling said last mentioned closing spring to the other lever at one side of its pivot.

40 4. In a door closer, stationary abutments carried respectively by a door and a door frame, a lever pivotally supported adjacent to each of said abutments, a member movably coupling said levers, a closing spring bearing against one of said abutments, means for coupling said closing spring to one of 45 said levers at one side of its pivot, another closing spring bearing against the other abutment.

ment, means for coupling said last mentioned closing spring to the other lever at one side of its pivot, and a governor spring connecting said coupling member and one of said levers.

5. In a door closer, casings adapted to be connected respectively to a door and a door frame and each including an abutment, a closing spring and a checking spring bearing against the abutment of one of said casings, 70 a lever pivotally supported and provided with bearings spaced apart, connecting means between said bearings and said closing spring and checking spring, another closing spring bearing against the abutment of the other casing, another lever connected to said last-mentioned closing spring, a segmental member pivotally supported and provided with a plurality of concentrically arranged apertures, pins detachably connecting 75 said levers to the apertures of the segment and a governor spring connecting said segmental members and one of said levers.

6. In a door closer, casings adapted to be connected respectively to a door and a door frame and each including an abutment, a closing spring and a checking spring bearing against the abutment of one of said casings, pull rods extending respectively through said springs and having adjusting 80 nuts bearing against said springs thereon, a lever pivotally supported and provided with bearings spaced apart, connecting means between said bearings and said pull rods, another closing spring bearing against the 85 abutment of the other casing, a pull rod extending through said last-mentioned spring and carrying an adjusting nut bearing against the spring, another lever connected to said last-mentioned pull rod, a segmental member pivotally supported and provided with a plurality of concentrically arranged 90 apertures, and pins detachably connecting said levers to the apertures of the segment.

7. In a door closer, casings adapted to be 95 connected respectively to a door and a door frame and each including an abutment, a closing spring and a checking spring bearing against the abutment of one of said casings, a lever pivotally supported and provided at 100 one end with bearings spaced apart and with a plurality of apertures spaced apart at the other end, connecting means between said bearings and said closing spring and checking spring, another closing spring bearing 105 against the abutment of the other casing, another lever connecting at one end to the said last-mentioned closing spring, a segmental member pivotally supported and provided with a plurality of concentrically arranged 110 apertures, and pins detachably connecting the apertures of said levers to the apertures of the segments.

8. In a door closer, a lever pivoted to a 115 door frame, a closing spring connected to the 120

lever at one side of its pivot, a checking spring connected to the lever at the other side of its pivot, another lever pivoted to a door and movable therewith, and a coupling member uniting said levers.

9. In a door closer, a lever pivoted to a door frame, a closing spring connected to the lever at one side of its pivot, a checking spring connected to the lever at the other side of its pivot, another lever pivoted to a

door and movable therewith, a coupling member uniting said levers, and a governor spring connecting said coupling member and one of said levers.

In testimony whereof I affix my signature 15 in presence of two witnesses.
